United States Patent Office

Des. 214,587
Patented July 1, 1969

214,587

ACCESSORY TRAY FOR A VACUUM CLEANER OR THE LIKE

Lee Wolf, Cincinnati, Ohio, assignor to Haley Corporation, Cincinnati, Ohio, a corporation of Ohio

Filed Jan. 24, 1968, Ser. No. 10,293

Term of patent 14 years

Int. Cl. D7—06

U.S. Cl. D49—17

FIG. 1

FIG. 2

FIG. 3

I claim:

The ornamental design for an accessory tray for a vacuum cleaner or the like, substantially as shown.
